(57) **CLAIM**

The ornamental design for a smartphone mount for binoculars and monoculars as shown and described.

DESCRIPTION

FIG. 1 is a rear perspective view of a smartphone mount for binoculars and monoculars showing my new design;

FIG. 2 is a rear view of the smartphone mount for binoculars and monoculars of FIG. 1;

FIG. 3 is a front view of the smartphone mount for binoculars and monoculars of FIG. 1;

FIG. 4 is a left side view of the smartphone mount for binoculars and monoculars of FIG. 1;

FIG. 5 is a right side view of the smartphone mount for binoculars and monoculars of FIG. 1;

FIG. 6 is a bottom view of the smartphone mount for binoculars and monoculars of FIG. 1;

FIG. 7 is a top view of the smartphone mount for binoculars and monoculars of FIG. 1;

FIG. 8 is a front perspective view of the smartphone mount for binoculars and monoculars of FIG. 1, shown in an environment of use;

FIG. 9 is another right side view of the smartphone mount for binoculars and monoculars of FIG. 1, shown in an environment of use; and,

FIG. 10 is another top view of the smartphone mount for binoculars and monoculars of FIG. 1, shown in an environment of use.

The broken lines in the drawings depict unclaimed environmental subject matter.
